 Jr., Clifton, N. J., assignors to Curtiss-Wright
 Corporation, a corporation of Delaware

Application March 14, 1951, Serial No. 215,418

10 Claims. (Cl. 170—160.52)

1

This invention relates to aeronautical propellers and is concerned particularly with an arrangement for mounting the blades of a propeller in a hub in such a manner that the blades are controlled for pitch change but otherwise are free to articulate universally to minimize bending moments in the propeller blades and hub.

While articulated propeller blade mountings have been taught broadly in the prior art, the structural features involved in known mountings have many disadvantages from the standpoint of weight, strength and complication. Still, a structurally adequate articulated blade mounting holds considerable promise for weight reduction in a propeller. If the bending moments in the propeller blade are materially reduced by articulation, the amount of material in a propeller blade may be lessened with consequent lightening thereof, with consequent reduction in the centrifugal force imposed on the rotating propeller blade which again enables a weight reduction in the blade. A propeller blade in operation is stabilized in a generally radial direction in its hub by the action of centrifugal force. Other forces imposed on the blade in operation include aerodynamic and vibratory loadings, torque loading, and thrust loading. These latter loadings tend to make the propeller blade depart from a normally radial position. If the blade mounting is so constructed as to allow of such departure rather than having the blade rigidly mounted, the position of the blade in operation will still be effective for aircraft propulsion while permitting the above indicated minimization of stresses in the propeller blade and also in the propeller hub.

It is a particular object of this invention to provide a propeller blade mounting in a propeller hub which allows limited universal movement of the propeller blade with respect to a radius of the propeller hub normal to the propeller rotational axis. The blade may tilt forwardly or rearwardly from the plane of rotation and may tilt in advance or in retard of a hub radius with respect to the direction of hub rotation. Also, the blade may move in any combination of the above two modes of movement. It is a further object of the invention to provide a mounting wherein the blade will be constrained to a controlled pitch position regardless of the direction and magnitude of the aforesaid blade tilting.

To accomplish the above objectives, a more or less conventional propeller blade is secured

2

in a propeller hub socket by means of an anti-friction universal joint of spherical configuration which is capable of assuming the radial centrifugal loading on the propeller blade and other forces imposed on the blade. The joint, briefly, comprises two arrays of small barrel-shaped rollers oriented to provide intersecting rocking axes for the joint at 90 degrees to one another, the rollers being disposed between sets of hardened steel races having spherically segmental configuration. The invention further includes the provision of retainers to hold the rollers in their best orientation and includes means to urge the retainers and rollers toward a controlled position relative to the socket axis so that they cannot drift away from the position where full bearing capacity is assured.

Additional objects of the invention will be appreciated from reading the annexed detailed description in connection with the drawings, and it is to be understood that the description and drawings reveal only a single embodiment of the invention. The scope of the invention is as broad as the subjoined claims will permit.

25 In the drawings, wherein similar reference characters indicate similar parts,

Fig. 1 is a fragmentary longitudinal section through a portion of a propeller embodying the invention;

30 Fig. 2 is a fragmentary section on the line 2—2 of Fig. 1;

Fig. 3 is a partial plan view of a developed multiple roller bearing retainer used in the invention showing a preferred disposition of the rollers;

35 Fig. 4 is a fragmentary view of one of the roller bearing race assemblies wherein the races are offset relative to one another at the maximum angularity of articulation of the blade with respect to its hub; and

40 Fig. 5 is a diagram of the arrangement of roller bearings in the invention.

A propeller hub is indicated at 6 and is provided with a plurality of blade sockets one of which is indicated at 7. The hub, in conventional manner, is provided with a bore 8 equipped with internal splines 9 by which the propeller may be mounted on a suitable propeller shaft. In the recess 10 of each socket 7 is a platform 11 providing a positioning point for a propeller blade 12 secured within the socket. The blade at its inner end is provided with an integral flange 14 against which is seated a member 15 having a spherical end 16, this spherical end 55 engaging a cup 17 whose inner end rests against

the seat 11. Also, the cup 17 is secured to other parts of the structure, to be described, by a Belleville washer 18 to hold the bearing system up to the race 28 in assembled relation with the blade and cup. The member 15 has a spline connection 19 with the interior of the blade 12 to constrain the member 15 and the blade 12 for rotation with one another.

Embracing the exterior of the inner end of the blade 12 and resting against the flange 14 is a race member 20, the member 20 being split on a diameter for assembly over the blade shank and being formed exteriorly with a spherical surface 21 whose center is the center 22 of the ball 16. Embracing the race 20 is a first intermediate annular race 24 which is spherically formed at its inner surface 25 and at its outer surface 26, both of these surfaces 25 and 26 also being struck from the center 22. The race surfaces 21 and 25 provide for longitudinal rocking or articulation of the blade about a first axis substantially normal to the socket axis, passing through the center 22. Further embracing the race member 24 is a second intermediate race member 28 whose inner surface 29 is spherically formed from the center 22 and whose outer surface 30 is formed as a cone with a plurality of annular ball races 31, these grooves being concentric with the socket. The race surfaces 26 and 29 provide for rocking or articulation of the blade about an axis normal to the socket axis and normal to said first axis parallel to the propeller shaft and passing through the center 22.

Screwed within the outer end of the hub socket 7 is an outer race 32 formed externally as an internal nut to engage the socket 7 at threads 33 to secure the bearing assembly within the socket, and formed at 34 as an internally conical bearing race having annular grooves 35 complementary to the annular grooves 31 of the race 28 and concentric with the socket. Between the annular grooves 35 and 31 are a plurality of bearing balls 37 retained in conical shell-like retainers 38, enabling the race 28 to move freely, with respect to the hub socket. 45

Roller and ball bearings, to be described, are disposed between the races 20 and 24, and between the races 24 and 28 so that the blade proper along with the said races are all constrained to rotate in unison relative to the socket. 50 Rotational position of this assembly about the blade axis establishes the pitch setting of the propeller blade and is accomplished by an adapter 39 splined at 40 to the race 28 and splined at 41 to a blade gear 42 controlled in its position by an appropriate pitch changing mechanism, not shown. The blade gear holds the rim of the washer 18 and is secured to the adapter 39; the adapter 39, is secured to the race 28 by screws in addition to the spline connection 40. The pitch changing mechanism, as is well known in the art, is adapted to control the pitch of a number of propeller blades simultaneously and may include a master gear, concentric with the propeller shaft, engaging the gears 42 on the 55 several blade assemblies of the propeller.

The gears 42 and the above suggested master gear are merely exemplary of a means for connecting the pitch changing mechanism to the blades. These are not intended to limit the scope of the invention.

Between the races 20 and 24 are disposed a large plurality of short bearing rollers, the rollers being arranged so that as large as possible an area of the two races are covered by the rollers. 75

Fig. 3 shows a developed plan of the arrangement of rollers each carrying the designation 44, the rollers being retained in a shell-like annular member 46. These rollers enable the race 20 to rock with respect to the propeller hub in the fore-and-aft plane. The races 20 and 24 are locked against relative rotation about the axis of the propeller blade by rows of balls 48 shown in Figs. 1 and 3 which are larger in diameter than the rollers 44 and which seat in grooves 50 in the races 20 and 24, the grooves being segments of a great circle on the spherical surfaces of the races.

The orientation of the rollers 44 on the race surfaces and in the retainer 46 is important. In order to roll with minimum sliding or scrubbing on the spherical race surfaces, the axis of each roller must intersect the appropriate axis of articulating rotation, passing through the sphere center 22 and normal to the plane occupied by the keying balls 48. Such articulating axis is noted in Fig. 3 at 49 for the rollers 44; the articulating axis for the other set of rollers 44' lies at a right angle to the axis 49. Each roller 44 rolls in a plane parallel to the plane of the balls 48 and in a tilted attitude established by its location on the spherical race surfaces. This is shown diagrammatically in Fig. 5.

Actually, the same functional effect could be obtained if the race surfaces 21, 24 were cylindrical, with the race surfaces 26, 29 also cylindrical but with the cylinder axis oriented at a right angle to the axis of cylindrical surfaces 21, 24. But if the bearing assembly were so constructed, a great increase in mass and bulk would result, making the joint arrangement impractical for aeronautical propeller use. Also, roller orientation problems could be obviated by substituting balls for the rollers 44. Rollers, however, have a greater load capacity, and are preferred since the centrifugal loading on the bearings is high, due to rotation of the propeller about the axis of the propeller hub.

In the same manner as described above, rollers 44' are disposed between the facing spherical surfaces 26 and 29 of the races 24 and 28, the rollers being retained in an annular disc-like retainer 46'. The rollers 44' are oriented to enable swinging of the propeller blade with respect to the socket transversely to the propeller axis, or in the plane of rotation of the propeller. As in the previously described arrangement, balls 48' lock the races 28 and 24 from relative rotation about the propeller blade axis, these keying balls 48' shown in Fig. 2, engaging great circle tracks 50' in the spherical faces 26 and 29 of the races 24 and 28.

In Fig. 3, the annular roller retainer 46 is shown as though it were planar, with the rollers 44 in axially parallel relation and parallel to the rocking axis 49. When this retainer is cupped into spherically segmental form to occupy its proper position between the spherically segmental roller races, each individual roller, and the cutout in the retainer in which each roller is disposed, is reoriented so that each roller axis will intersect the axis 49 as shown in Fig. 5. Thereby, each roller will roll without substantial endwise sliding in a circular path parallel to equatorial circle of the sphere. The keying balls 48 roll in a segment of the equatorial circle.

The race 28 as indicated previously, may rotate about the axis of the propeller blade on the bearing balls 37 under the influence of the gear 42 to effect pitch change of the propeller blade.

When the race 28 is so rotated, pitch changing rotation is imparted to the race 20 through the balls 48' and 48 and thence through spline connections 52 and 54 from the race 20 to the adapter 15 and thence to the blade 20 through the spline connection 19. The two sets of rollers 44 and 44' provide large bearing area to sustain the centrifugal force imposed upon the blade in operation while allowing free universal action of the blade for articulating purposes. Each roller 44 and 44' is slightly barrel shaped so that it will have substantially line contact on the inner spherical surfaces of the races 28 and 24.

Fig. 3 shows the pattern of rollers to enable rocking of the related races with respect to one another so that there will always be rollers between the coacting race faces. For instance, if one race is rocked with respect to the other race as is shown in Fig. 4, a portion of each race will overhang the other, but the overlapped race portions will be adequately provided with loaded rollers. It will be noted in the zone 55 in Fig. 3 that the overall span of the rollers is less than the overall span at 56. This is necessary to avoid rollers leaving one of the races when the races are overlapped relative to each other.

Since the sets of rollers 44 and 44' lie between race surfaces which have oscillatory motion with respect to each other and since the race surfaces are not complete annuli, it is necessary to restrain the roller retainers 46 and 46' so that they will not creep out of their correct relationship with the coacting race surfaces during operation of the propeller. The retainers could be positively held to their proper orbit. Preferably, they may at all times be urged toward a correct position between the races by elastic means which impose a force upon them. The retainer 46 is provided with ears 60 extending beyond the roller carrying portions thereof, these ears being disposed on a great circle aligned with the keying balls 48. The outer end of each ear 60 is inwardly formed as at 62 with a wedge arrangement, and springs 63 and 64 are disposed on either side of the wedge 62. The spring 63 acts between the wedge 62 and the inner race 20, while the spring 64 acts between the wedge 62 and a socket 66 carried by the adapter 39. The opposed sets of springs as noted in Fig. 1 continuously tend to hold the retainer 46 in a position such that the rollers and balls 44 and 44' will lie in contact with the races, the retainer shifting angularly through half the angle of race shift.

In the same manner, the retainer 46' as shown in Fig. 2 carries ears 60' terminating in wedges 62'. Springs 63' and 64' respectively act between portions of the race 20 and wedge, and between the wedge and sockets 66' carried by the adapter 39. The two pairs of springs 63, 64 and 63', 64', at right angles relative to the blade, serve to urge the retainers, balls 48, 48' and rollers 44, 44' to their proper positions along their respective rectilinear lines of action.

Since the hub system contains lubricant, sealing provisions to prevent the escape of lubricant are required for the articulating mechanism. To this end, a resilient boot 68, of annular form, is provided for each blade, one end of the boot having a bead 70 secured to the blade shank by an annular ring 70, and the other end of the boot being beaded at 71 and being secured to the intermediate race 28 by a ring 72 and splines 73. A portion of the bead 71 engages a flange 74 on

the retaining nut 32 in sliding sealing engagement. The spline connection 73 enforces the sealing boot 68 to rotate with the propeller blade when pitch changes are made so that the boot is not twisted.

The blade retaining nut 32, when properly screwed into the hub socket 7 to provide firm contact of all of the bearings, and to seat the ball 16 on the socket 17, is held in place by locking lugs and screws 76 securing the blade nut 32 against rotation relative to the socket 7.

Other seals of more or less conventional character are provided in the system where necessary. For instance, a seal ring 77 is disposed between the member 15 and the blade shank to prevent lubricant leakage into the blade hollow; also a seal ring 78 is provided between the blade nut and the socket to prevent leakage through the threads 33.

From the structure described it will be seen that the propeller blade 12 may articulate in its socket about the center 22 through limited angles, either in the plane of rotation or in the direction of flight or in any combination of these two modes of motion. This articulation has complete freedom with minimum friction and virtually no restraint. The amount of articulation may be of the order of about 8 degrees as noted by the dotted line outline of the propeller blade in Fig. 2. Limits of articulation are established by a bumper flange 80 on the propeller blade shank which at the limit of articulation may contact the inner edge of the outer race 28 as at 82. As has been shown in the prior art on articulated blade mountings, elastic bumpers may be used in the system at the limit of blade articulation, if desired.

A further point in the construction herein shown is that blade drive for pitch change is accomplished without introducing motion errors or restraint to articulation. In the construction of the various bearing retainers previously described, suitable devices may be used, in accordance with usual practices in the bearing art, for holding the various rollers and balls in the retainers so that they will not drop out if the race surfaces become separated as during assembly and disassembly of the mechanism.

Though but a single embodiment illustrating the invention has been shown and described, it is to be understood that the invention may be applied in other and various forms. Changes may be made in the arrangements, without departing from the spirit of the invention. Reference should be had to the appended claims for definitions of the limits of the invention.

We claim:

1. An aircraft propeller comprising a hub including a socket extending radially outwardly from the hub axis, an inwardly facing race secured within said socket, a second race having an outer surface in thrust bearing relation to the first race and rotatable relative thereto about the socket axis and having an inner face of spherically segmental form, a propeller blade in said socket having a shank passing through said races and having at its inner end an outwardly facing spherically segmental blade race, a plurality of rollers between and in rolling engagement with said spherically segmental race surfaces enabling articulation of said blade relative to said socket, keying means engageable with and between the second race, the blade race and blade to enforce joint rotation thereof about the socket axis, and means drivably connected to

turn said second race to effect changes in pitch of the propeller blade.

2. An aircraft propeller comprising a hub including a socket extending radially outwardly from the hub axis, an inwardly facing race secured within said socket, a second race having an outer surface in thrust bearing relation to the first race and rotatable relative thereto about the socket axis and having an inner face of spherically segmental form, a propeller blade in said socket having a shank passing through said races and having at its inner end an outwardly facing spherically segmental blade race, a plurality of rollers between and in rolling engagement with said spherically segmental race surfaces enabling articulation of said blade relative to said socket, keying means engageable with and between the second race, the blade race and blade to enforce joint rotation thereof about the socket axis, means drivably connected to turn said second race to effect changes in pitch of the propeller blade, a cage holding said rollers in spaced relation to one another and lying between said spherically segmental race surfaces, and elastic means acting between said second race, blade race, and cage, and urging said cage to a controlled position relative to said segmental races.

3. In an aircraft propeller comprising a hub having a socket extending radially outward therefrom and a blade disposed in said socket, bearing means between the hub and the inner end of said blade defining a pivot center for articulation of the blade with respect to the hub, a plurality of spherically segmental annular races stacked upon one another, one of said races being secured to the blade and a second race outwardly thereof being journaled in said socket for rotation relative thereto about the hub axis, anti-friction thrust rollers disposed between said races, means engaging said races to constrain them to rotation in unison, and means to rotate said second race about the socket axis to impart pitch change to the blade.

4. In an aircraft propeller comprising a hub having a socket extending radially outward therefrom and a blade disposed in said socket, bearing means between the hub and the inner end of said blade defining a pivot center for articulation of the blade with respect to the hub, a plurality of spherically segmental annular races stacked upon one another, one of said races being secured to the blade and a second race outwardly thereof being journaled in said socket for rotation relative thereto about the socket axis, anti-friction thrust rollers disposed between said races, said stack of races including an intermediate race between the two mentioned, means engaging said races to constrain them to rotation in unison, means to rotate the second race about the socket axis to impart pitch change to the blade, the rollers between the blade-secured race and the intermediate race being oriented for swinging of the blade about one axis normal to the socket axis, and the rollers between the intermediate race and said second race being oriented for swinging of the blade about another axis normal to the socket axis and normal to said one axis.

5. In an aircraft propeller, a hub having a socket extending radially outward therefrom, a blade having an end disposed in said socket, an articulating bearing securing the blade in said socket comprising a first inwardly facing spherically segmental race secured within the socket,

an outwardly facing spherically segmental race secured to the blade and lying inwardly of the first race, both of said races being annular and embracing the blade, a plurality of substantially cylindrical rollers between and engaging said races for carrying loads imposed between blade and socket, and a spherically segmental retainer between said races having apertures therein within which said rollers are disposed, said apertures comprising substantially rectangular openings disposed to hold each said roller in an alignment such that all roller axes intersect an articulation axis passing through the center of the sphere defining the spherically segmental race surfaces.

6. In an aircraft propeller, a hub having a socket extending radially outward therefrom, a blade having an end disposed in said socket, an articulating bearing securing the blade in said socket allowing blade articulation about first and second relatively angled axes normal to the blade socket axis, said bearing comprising an outer race annular member carried by the socket and rotatable about the socket axis and having an inwardly facing first race surface concentric with said first axis, an intermediate race member having an outer race surface concentric with said first axis and facing said first race surface and an inner race surface concentric with said second axis, an inner annular race member embracing and secured to said blade having an outer race surface concentric with said second axis and facing said inner race surface, roller means between said outer and intermediate race members, and between said intermediate and inner race members, and means to retain said roller means between and in engagement with respective race members.

7. In an aircraft propeller, a hub having a socket extending radially outwardly therefrom, a blade having an end disposed in said socket, an articulating bearing securing the blade in said socket allowing blade articulation about first and second relatively angled axes normal to the blade socket axis, said bearing comprising an outer race annular member carried by the socket and rotatable about the socket axis and having an inwardly facing first race surface concentric with said first axis, an intermediate race member having an outer race surface concentric with said first axis and facing said first race surface and having an inner race surface concentric with said second axis, an inner annular race member embracing and secured to said blade having an outer race surface concentric with said second axis and facing said inner race surface, roller means between said outer and intermediate race members, and between said intermediate and inner race members, means to retain said roller means between and in engagement with respective race members, and means engaging said race members and blade to rotate said bearing and blade jointly in said socket about the socket axis.

8. In an aircraft propeller, a hub having a socket extending radially outwardly therefrom, a blade having an end disposed in said socket, an articulating bearing securing the blade in said socket allowing blade articulation about first and second relatively angled axes normal to the blade socket axis, said bearing comprising an outer race annular member carried by the socket rotatable about the socket axis and having an inwardly facing first race surface concentric with said first axis, an intermediate race member

having an outer race surface concentric with said first axis and facing said first race surface and having, an inner race surface concentric with said second axis, an inner annular race member embracing and secured to said blade having an outer race surface concentric with said second axis and facing said inner race surface, roller means between said outer and intermediate race members, and between said intermediate and inner race members, means to retain said roller means between and in engagement with respective race members, said retaining means being annular in form and embracing the blade, and elastic means acting between the retaining means and the associated race members urging said retaining means to a controlled position between the race members between which the retaining means is disposed.

9. In an aircraft propeller, a hub having a socket extending radially outwardly therefrom, a blade having an end disposed in said socket, an articulating bearing securing the blade in said socket allowing blade articulation about first and second relatively angled axes normal to the blade socket axis, said bearing comprising an outer race annular member carried by the socket rotatable about the socket axis and having an inwardly facing first race surface concentric with said first axis, an intermediate race member having an outer race surface concentric with said first axis and facing said first race surface and having, an inner race surface concentric with said second axis, an inner annular race member embracing and secured to said blade having an outer race surface concentric with said second axis and facing said inner race surface, roller means between said outer and intermediate race members, and between said intermediate and inner race members, means to retain said roller means between and in engagement with respective race members, said race surfaces all comprising spherical segments having a common center.

10. In an aircraft propeller, a hub having a socket extending radially outwardly therefrom,
